UNITED STATES PATENT OFFICE.

NICOLA PEDULLA, OF MACDONALDTON, PENNSYLVANIA.

MINING-MACHINE.

1,358,984.

Specification of Letters Patent. Patented Nov. 16, 1920.

Application filed December 22, 1919. Serial No. 346,465.

To all whom it may concern:

Be it known that I, NICOLA PEDULLA, a citizen of the United States, residing at Macdonaldton, in the county of Somerset and

5 State of Pennsylvania, have invented certain new and useful Improvements in Mining-Machines, of which the following is a full, clear, and exact specification.

This invention relates to machines for 10 mining soft coal or other substances, and has for its object to provide a simple form of machine which can be easily handled and operated or controlled by a single workman.

It is the aim of the invention to produce a 15 small machine having a small number of boring tools simultaneously actuated by an electric motor, to provide a simple form of driving means between the motor and tools, and to supply means for enabling the operator 20 to advance or move the machine and hold it in proper position during each cutting operation. Another object is to provide means for adjusting the motor on the machine to take up slack in the sprocket chain 25 which is used as the driving medium between the motor and boring tools. Other objects will appear as the description proceeds.

The invention will be first hereinafter described in connection with the accompanying 30 drawings, which constitute part of this specification, and then more specifically defined in the claims at the end of the description.

35 In the accompanying drawings, wherein similar reference characters are used to designate corresponding parts throughout the several views:

Figure 1 is a side elevation of a coal cutting machine constructed substantially in accordance with this invention, said machine being shown supported in position as when cutting a kerf about half way up a wall of coal.

40 Fig. 2 is a plan view of the machine with the ends of the tool-carrying shafts being broken away.

Fig. 3 is a similar view showing parts in section and the tools on the ends of the 45 shafts.

Fig. 4 is a section on the line IV—IV of Fig. 3 and

Fig. 5 is an enlarged detailed section 50 through the key connection of the beveled pinion on one of the tool-carrying shafts, said shaft being also shown in engagement

with the bearing member extending across the front end of the machine casing.

A rectangular box or casing 1 carries the operating parts of the machine and is 60 mounted on wheels 2 placed one about midway of each side, as shown, so that said casing may be rocked or tilted on said wheels if desired during the operation of the machine for directing the boring tools along 65 a slight upward or downward incline as is sometimes advantageous. Extending into the casing 1 and projecting from the front end thereof is a bearing member 4 preferably of skeleton form, as indicated in Figs. 70 2 and 3, for reducing the weight thereof. A plurality of shafts 5, of which three are illustrated in the present embodiment of the invention, extend through passages in said bearing member 4 and have their rear ends 75 fitted or bearing in sockets 6 in the back end of the casing. Said shafts are enlarged, as at 3 between the front and rear ends of the casing and are retained against axial movement by said sockets 6 and the reduced forwardly extending portions 7 which fit in the bearing member 4.

On the front end portions 7 of the shafts 5 are mounted boring tools or bits 8 having flared cutting ends 9 which overlap each 85 other, the middle one being slightly in advance of the others, as shown in Fig. 3, so that said bits will make a continuous kerf in the wall of coal as at 10 in Fig. 1. The shafts are rotated by means of beveled pinions 11, one of which is keyed on each of the shafts, as at 12 in Fig. 5, said pinions meshing respectively with other beveled pinions 13 carried by short vertical shafts 14 journaled in the top 15 of the casing 1 and having sprocket wheels 16 mounted on their upper ends above the top of the casing, see Fig. 4. A sprocket chain 17 is passed around all of the sprocket wheels 16 on the three vertical shafts 14 and also around a sprocket 100 wheel 18 mounted on the armature shaft 19 of an electric motor 20 which is supported on a bracket 21 rising from the top 15 of the casing 1. The chain 17 may be tightened to take up slack by adjusting the motor toward 105 or away from the sprocket wheels 16. For this purpose, the bracket 21 is adjustably secured to the top of the casing by bolts 22 passed through slots 23, and an adjusting screw 24 is swiveled to the bracket 21 and threaded in the standard 25. When the bolts 22 are loosened, the bracket 21 and motor

95

105

110

carried thereby may be adjusted by turning the screw 24, after which the bolts 22 may be tightened to retain the new adjustment.

The middle one of the vertical shafts 14 is arranged slightly in advance of the others so as to insure the proper engagement of all of the sprocket wheels by the sprocket chain. The pinions 11 are keyed on the shafts 5 to mesh with the pinions 13 on the vertical shafts 14. The sprocket wheels 16 are preferably covered by a protective cage 27 to exclude coal dust and dirt therefrom, said cage or cover 27 extending over a considerable portion of the sprocket chain as well.

15 In operation, the machine is placed upon a suitable platform 28, Fig. 1, at the proper level in the mine chamber, the machine being shown in position for cutting a kerf about half way up the wall of coal. 20 Handles 29 are pivoted at 30 to the sides of the casing 1 and extend rearwardly therefrom so that the operator, who preferably sits on the platform behind the machine, may push it forward on the wheels 2 to feed 25 the boring tools into the kerf as their cutting or boring operation continues. The length of the boring tools and the projecting portions 7 of the shafts 5 are preferably such as to permit of cutting a kerf about 30 four feet deep.

The handles 29 have forwardly extending portions 31 adapted to act as brakes on said wheels when the rear ends of said handles are pressed upward, thereby enabling the 35 operator to overcome the tendency of the machine to move backward when the boring tools are being fed forward against the wall of coal. The interior of the casing may be

kept supplied with sufficient oil or grease to lubricate the shafts and pinions, said lubricant being introduced through a filling opening or nozzle 32 in the top 15 of the casing 1 as shown in Fig. 2.

Having thus described my invention what I claim as new and desire to secure by Letters Patent of the United States is:—

1. In a mining machine of the character described, the combination with a casing, of a plurality of boring tools, and means for rotating said tools comprising pinions connected to the tools, vertical shafts journaled in the casing, pinions on the lower ends of said shafts and meshing with the pinions connected to the tools, horizontal sprocket wheels on the upper ends of said vertical shafts, a horizontal driven sprocket wheel also mounted on the casing in the plane of the other sprocket wheels, and a sprocket chain passed around all of the sprocket wheels for simultaneously actuating all of the tools.

2. In a mining machine, the combination with a casing, of a plurality of boring tools, horizontal sprocket wheels operatively connected for driving said tools and all arranged in the same plane, a motor horizontally adjustable on the machine, a sprocket wheel on the armature shaft of the motor and arranged in the plane of the other sprocket wheels, and a sprocket chain passed around all of said sprocket wheels for the purpose specified.

In testimony whereof I have signed my name to this specification.

NICOLA PEDULLA.
